JOHN ABSTERDAM, OF NEW YORK, N. Y.

Letters Patent No. 84,335, dated November 24, 1868.

IMPROVEMENT IN APPARATUS FOR MAKING STEEL AND REFINING IRON.

The Schedule referred to in these Letters Patent and making part of the same.

To all whom it may concern:

Be it known that I, JOHN ABSTERDAM, of the city, county, and State of New York, have invented a new and improved Apparatus for Making Steel and Refining Iron; and I do hereby declare the following to be a full, clear, and exact description thereof, which will enable those skilled in the art to make and use the same, reference being had to the accompanying drawing, forming part of this specification, in which drawing—

Figure 1 represents a vertical central section of this invention.

Figure 2 is a transverse section thereof, taken in the plane indicated by the line x x , fig. 1.

Figures 3 and 4 are details, which will be referred to as the description progresses.

Figure 5 shows a modification thereof.

Similar letters indicate corresponding parts.

This invention relates to an apparatus which is intended to carry out a process for refining iron and making steel *in vacuo*, for which Letters Patent were granted to me, January 23, 1866, and which also embodies several valuable and important improvements not mentioned in the aforesaid patent.

These improvements consist in the arrangement of a spark-arrester, attached to the mouth of the converter in such a manner that the sparks or solid particles carried out of the converter by the current of air are retained, and the clogging up of the exhauster or suction-apparatus is thereby prevented; also, in the arrangement of a hollow tubular pivot, in combination with the spark-arrester, and with the steam-supply pipe of the exhauster, in such a manner that said spark-arrester and exhauster can be swung back or raised from the mouth of the converter without breaking the connection of the steam-supply pipe; further, in the arrangement of a rising and falling perforated chamber, in combination with the converter, and with a pipe supplying hydrocarbon-gas or air under pressure, or both, in such a manner that, by pressing said chamber up against the bottom of the converter, either air or gas, or both, can be injected into the converter with great ease and convenience; also, in the arrangement of movable plugs, in combination with the rising and falling chamber, and with the holes in the bottom of the converter, in such a manner that, by raising said chamber, the holes in the converter can be plugged up simultaneously, and the operation of the apparatus is thereby materially facilitated.

A represents a converter, which is hung on trunnions, a , similar to cupolas used in olden times in foundries. On the mouth of this converter is placed the spark-arrester, B, which is composed of a metallic jacket, lined with fire-brick or other refractory material, and which is suspended on a pivot, b , so that it can be readily swung up from the mouth of the converter, or let down thereon, as may be desired.

Instead of constructing the spark-arrester in the form shown in fig. 1, however, it might be constructed

as indicated by fig. 5, where the mouth of the converter is inclined, and fits against the correspondingly-inclined mouth of the spark-arrester. In this case the spark-arrester can remain stationary, and it does not interfere with the necessary motion of the converter.

In the interior of said spark-arrester are placed a concave-retainer, a' , and one or more screens, b' , which serve to arrest the solid impurities which are carried out of the mouth of the converter, so that said impurities are prevented from clogging up the suction-apparatus or exhauster C.

This exhauster is firmly connected to the spark-arrester by a pipe, d , and it consists of an adjustable nozzle, e , which is in line with a conical spout, f , and at right angles with the connecting-pipe d , so that, by passing a current of steam through the nozzle e , a partial vacuum is produced in the pipe d , the spark-arrester B, and the converter A, and the external air is caused to rush in through the openings g g^* , provided for this purpose in the bottom and sides of the converter, and to permeate the molten metal in said converter, as has been fully described in my Letters Patent of January 23, 1866.

The exhauster C is supplied with steam by means of a pipe, h , which connects with the bearing i of the pivot b , on which the spark-arrester is hung, and said pivot is made hollow or tubular, being closed at one end, and connected at its opposite open end to a steam-generator of any suitable construction.

That portion of said tubular pivot which is situated in the interior of the bearing i , is perforated with a hole, j , which registers with the mouth of the pipe h , when the spark-arrester is turned down upon the mouth of the converter, but when the spark-arrester is raised or swung off from the mouth of the converter, the hole j , in the tubular bearing i , is closed, and the communication between the steam-generator and the exhauster is shut off.

The bottom of the converter A is flat, and under it is placed a chamber, D, which is provided with a tubular shank, k , and the top of which is perforated with a series of holes, l , corresponding in number and position to the holes in the bottom of the converter.

The shank k of the chamber D is fitted into a socket, m , which communicates with a pipe, n , and the joint between said shank and the socket is rendered tight by a stuffing-box, o .

A lever, p , which embraces the shank k of the chamber D, serves to impart to said chamber a rising and falling motion, so that the upper surface thereof can be pressed up tight against the bottom of the converter, or adjusted at any desired distance therefrom.

The pipe n communicates, by means of a pipe, q , with a vessel containing hydrocarbon-gas or liquid, and, by means of a branch-pipe, r , with an air-forcing apparatus.

The hydrocarbon-gas or liquid is used to supply an additional amount of fuel to the molten metal in the

converter, and this fuel may be introduced into the converter either by the suction of the exhauster C, or by means of a forced current of air admitted through the branch-pipe r, or by the suction and the forced current combined.

If the fuel is to be introduced merely by suction, I supply the chamber D with a series of nipples, s, as shown in fig. 1 of the drawing.

The hydrocarbon-gas, admitted through the pipe q, on issuing from these nipples, mingles with the air, and is carried into the converter, together with such air, by the suction of the exhauster.

If hydrocarbon-liquid is used, I make the nipples s in the form of small wick-tubes, as shown in fig. 4, and, by introducing into these tubes suitable wicks, the hydrocarbon-liquid, as it rises in the chamber D, can be ignited, and the gases resulting from this combustion are carried in the converter, with the air, by the suction of the exhauster.

The tips of the nipples s are conical, and they fit into the countersunk ends of the holes g in the bottom of the converter, so that, by raising the chamber D, the tips of the nipples can be pressed into the openings g.

For the purpose of plugging up the holes g, I use movable plugs t, (see fig. 3,) which are made in the form of caps, to fit over the nipples s. After those plugs have been adjusted on the nipples, the chamber D is raised, and all the holes g in the bottom of the converter are plugged up simultaneously.

In order to perform this operation of plugging without fail, it is necessary to coat the plugs with loam or other suitable material, capable to form a luting in the holes g.

In some cases it is desirable to introduce fuel in a powdered or solid state, and to effect this purpose I have made holes g* in the sides of the converter. With these holes I connect hoppers, through which the powdered fuel is introduced, and the suction of the exhauster carries the fuel into and through the molten metal.

If a forced current of air is to be used, in combination with the suction, or independent thereof, I remove the nipples s, and place a suitable packing-piece on the top of the chamber D. By pressing the chamber up against the bottom of the converter, a forced current of air can be injected through the holes g with ease and convenience.

By means of this apparatus, I am enabled to subject the iron in the converter to a current produced by suction, either alone, or in combination with a forced current; I am enabled to introduce fuel into the molten metal, either by suction, or by a forced current; I am enabled to plug up the holes in the bottom of the converter simultaneously, simply by raising the chamber D; and, finally, I am enabled to regulate the supply of air and fuel with the greatest accuracy, so that the process of refining iron or making steel can be effected without trouble or uncertainty.

The operation of my invention is as follows, viz:

In order to refine pig-iron, or convert the same into steel, I first kindle a fire in the converter A, so as to heat its interior fire-lining to a red or white heat, as the case may require. In the mean time I melt the pig-iron in a cupola or reverberatory furnace, if desired, in the usual manner for melting iron in iron-foundries.

After the iron is melted, and the interior of the converter A is sufficiently heated, I incline said converter, with its mouth downwards, so as to discharge the fuel contained therein. I again turn up the converter in its natural position, the holes g g*, in the bottom and sides of the converter, being plugged up with the plugs coated with clay. I then draw out the melted pig-iron from the melting-furnace, and introduce it into the converter A by means of a ladle, or by placing the melting-furnace at such an elevation above the mouth

of the converter that, by simply tapping the melting-furnace in the usual manner, as now practised in iron-foundries for casting car-wheels, the molten iron will run into the mouth of the converter.

After having introduced the melted iron into the converter, I let down the mouth of the spark-arrester upon the mouth of the converter A, so as to make an air-tight joint, which joint I pack with tempered clay or other suitable luting.

Having thus made the connection between the spark-arrester B and converter A, I immediately open the stop-cock u on the pipe h, and set the exhauster C in operation, thereby causing and maintaining a continuous vacuum or partial vacuum in the converter. Now, just as soon as the vacuum-gauge indicates a sufficient amount of vacuum, I open the holes g g* in the bottom end of the converter, and the air rushes up through the molten metal in the converter. I then immediately open the cock on the pipe q, and allow the gas to flow through the chamber D, out of the holes l under the bottom of the converter, and the air and gas are both drawn into the converter through the molten metal, the air furnishing oxygen, and the carburetted gas furnishing fuel, for heating and continuing to heat the molten iron therein during its refining or its conversion into steel.

I commence by allowing a larger supply of fuel to enter with the air, when the converter is first set in operation, but, towards the end of the refining or converting-process of the molten metal, I diminish the supply of gas in such a manner that it will still continue to heat the metal to be refined or converted in the converter, and, at the same time, it allows the carbon of the converting-metal to be converted to burn away, together with the introduced fuel, until the requisite amount of carbon is contained in the molten metal under conversion; but, if it should be desired to pass the streams of air through a higher column of molten metal in the converter than the vacuum therein would permit, then I introduce just so much of a column of molten metal into the converter A as the vacuum will sustain therein without danger of the molten metal running out of the holes g g* in the bottom of the converter, when the same are open.

Having thus introduced the required amount of molten metal, and set the converter in operation, as before described, I immediately raise up the chamber D against the bottom of the converter, and cause a current of air from a blast-engine or other suitable apparatus to pass through the chamber D, up the holes g, and through the molten metal in the converter. In this case, I introduce the carburetted hydrogen-gas together with the air, and the amount of fuel admitted with the air is regulated as in the previous operation.

Now, in order to test the molten metal in the converter while the same is refining or converting, I introduce an iron rod through the holes g* in the side of the converter, and draw it out coated with molten metal contained therein, and try its quality by hammering, nipping, or otherwise, as the operator may find most convenient, and I repeat the operation every few seconds, until I find that the molten metal in the converter has arrived at its proper purification or conversion into steel.

Just as soon as the molten metal is properly refined or converted, I immediately stop the holes in the bottom and sides of the converter, and continue, for a little while, the suction or vacuum in the converter, so as to draw off the impurities that may remain in the molten mass; also to draw out of the molten metal the remaining particles of gas or air that might have been retained in said metal, more free from blow-holes than if the said particles of air or gas had remained in the same.

When the process of refining or converting has been finished, I lift up the spark-arrester, and incline the

converter, and turn the mouth downwards, so as to cause the metal to run out, and I cast the ingots either directly from the mouth of the converter, or by means of a ladle, as is generally practised in foundries.

If the process is to be continued, the converter is immediately recharged, and the operation is repeated, as above stated.

It will be readily understood that this process of refining iron or making steel, with the exception of the introduction of fuel, and the combination of the forced-air process with the suction-process, is precisely the same as described in my patent for refining iron or making steel *in vacuo*, dated January 23, 1866.

Having thus described my invention,

What I claim as new, and desire to secure by Letters Patent, is—

1. The spark-arrester B, in combination with the converter A, substantially as and for the purpose set forth.
2. The tubular pivot b, in combination with the spark-

arrester B, steam-pipe d, and exhauster C, substantially as and for the purpose described.

3. The chamber D, having a rising and falling motion in its socket m, in combination with an air or gas-supply pipe, one or both, and with the converter A, substantially as and for the purpose set forth.

4. The arrangement of nipples s in the chamber D, substantially as and for the purpose described.

5. The movable plugs t, in combination with rising and falling chamber D, substantially as and for the purpose set forth.

6. The pipe r, connecting with an air-forcing apparatus, in combination with the converter A and exhauster C, substantially as and for the purpose described.

JOHN ABSTERDAM.
